(57) **CLAIM**

I claim the ornamental design for a medical device, as shown
and described.

DESCRIPTION

FIG. 1 is a perspective view of an embodiment of the claimed
design;

FIG. 2 is a top view of the claimed design of FIG. 1;

FIG. 3 is a bottom view of the claimed design of FIG. 1;

FIG. 4 is a right side view of the claimed design of FIG. 1;

FIG. 5 is a left side view of the claimed design of FIG. 1;

FIG. 6 is a front view of the claimed design of FIG. 1;

FIG. 7 is a rear view of the claimed design of FIG. 1;

FIG. 8 is a perspective view of a second embodiment of the
claimed design;

FIG. 9 is a top view of the claimed design of FIG. 8;

FIG. 10 is a bottom view of the claimed design of FIG. 8;

FIG. 11 is a right side view of the claimed design of FIG. 8;

FIG. 12 is a left side view of the claimed design of FIG. 8;

FIG. 13 is a front view of the claimed design of FIG. 8;

FIG. 14 is a rear view of the claimed design of FIG. 8;

FIG. 15 is a perspective view of a third embodiment of the
claimed design;

FIG. 16 is a top view of the claimed design of FIG. 15;

FIG. 17 is a bottom view of the claimed design of FIG. 15;

FIG. 18 is a right side view of the claimed design of FIG. 15;

FIG. 19 is a left side view of the claimed design of FIG. 15;

FIG. 20 is a front view of the claimed design of FIG. 15; and,

FIG. 21 is a rear view of the claimed design of FIG. 15.

The ornamental design which is claimed is shown in solid
lines in the drawings. The broken lines in the drawings are for
illustrative purposes only and form no part of the claimed
design.
